UNITED STATES PATENT OFFICE

162,969

GAS HEATER

Franklin M. MacDougall, Kirkwood, Mo., assignor
to Jackes-Evans Manufacturing Company, St.
Louis, Mo., a corporation of Missouri

Application June 23, 1950, Serial No. 10,699

Term of patent 14 years

(Cl. D81—19)

To all whom it may concern:

Be it known that I, Franklin M. MacDougall, a citizen of the United States, and a resident of Kirkwood, in the county of St. Louis, State of Missouri, have invented a new, original, and ornamental Design for a Gas Heater, of which the following is a specification, reference being had to the accompanying drawing, forming part thereof.

Fig. 1 is a front perspective view of my new design for a gas heater,

Fig. 2 is a top plan view thereof,

Fig. 3 is a front elevational view thereof,

Fig. 4 is an elevational view of one end thereof, and

Fig. 5 is an elevational view of the opposite end thereof.

I claim:

The ornamental design for a gas heater, substantially as shown.

FRANKLIN M. MACDOUGALL.
